George D. Alderman
By his Attorney,
Nelson W. Howard

UNITED STATES PATENT OFFICE

GEORGE D. ALDERMAN, OF BEVERLY, MASSACHUSETTS, ASSIGNOR TO UNITED SHOE MACHINERY CORPORATION, OF PATERSON, NEW JERSEY, A CORPORATION OF NEW JERSEY

ABRADING MACHINE

Application filed July 12, 1929. Serial No. 377,765.

This invention relates to abrading machines and is herein illustrated as embodied in a buffing or scouring machine of the type set forth in United States Letters Patent No. 849,338, granted April 2, 1907, on the application of A. W. Rogers, the illustrated buffing tool being of the type shown in United States Letters Patent No. 1,575,686, granted March 9, 1926, upon the application of E. F. Hodgkins.

Fingerlike, rotatable buffing tools of the type shown in the last-mentioned patent are especially adapted for use in buffing or scouring the breasts of Louis heels and are usually, for the sake of greater accessibility, mounted upon the free end of a rotatable spindle. In such tools a replaceable abrasive, sleeve-like cover is mounted upon a supporting casing of resilient material, the casing being preferably of molded rubber closed at one end and secured at its other end to the rotatable spindle by means arranged to furnish an air-tight joint so that the tool may be inflated to secure the soft "touch" inherent in inflated buffing tools. When a tool of this type is arranged to be inflated, it is necessary to provide means for securing together the closed or free outer end of the tool and the spindle in such a fashion that the casing will be held against the axial stresses imparted by the air pressure, and regardless of whether or not it is inflated, it is necessary to provide means for resisting the torsional stresses set up in the free end of the resilient supporting casing by the application of work to the tool. Accordingly, one object of the invention is to provide improved means for insertion in the tool to resist both axial and torsional stresses.

With this in view and in accordance with a feature of the invention, the resilient casing of the illustrated tool is flanged outwardly at one end and is provided with a tubular insert to which the other end of the resilient casing is secured, the insert being also outwardly flanged at a locality adjacent to the flange of the resilient casing to enable both the resilient casing and the insert to be clamped, by a common means,

against a shoulder on a driven spindle. The insert thus serves not only to prevent twisting of that end portion of the resilient casing which is remote from the spindle, but it also resists such axial stresses as may be set up in the resilient casing by air pressure or otherwise.

Still other features of the invention are set forth in the accompanying specification and claims, reference being had to the accompanying drawing, in which

Fig. 1 is a vertical section through one of the heads of a Naumkeag machine having my improved tool applied thereto; and

Fig. 2 is a longitudinal section through the spindle of such a machine with the tool secured thereon.

The illustrated tool is designed for use in Naumkeag machines, such for example, as those of the type illustrated in Letters Patent of the United States No. 849,338 above referred to, in which a laterally extending head 10 is provided with bearings 12 and 14, within which there is supported for rotation a hollow spindle 16. Air under pressure may be supplied to this spindle through a passage 18 and a pulley 20 is provided for rotating the spindle. An abrading tool 21 is mounted upon the free end of the spindle 16, the tool 21 being designed for buffing or scouring the breasts of Louis heels.

This spindle 16 is provided with a shoulder 22 which is externally threaded at 24 and has a dowel pin 26 depending therefrom. The spindle is also provided with a tubular extension or stub 28 upon which is sleeved a rigid tubular lining or anti-twisting means 30 of brass or the like fitting said stub and secured inside a molded rubber supporting casing 32 as will be hereinafter described. This supporting casing 32 is adapted to receive a sleeve-like abrasive cover 34 held frictionally thereon when the tool is inflated. It will be noted that the inner end of the tubular insert 30 is provided with a flange 40 perforated to receive the dowel pin 26 so that said insert is held against rotation with respect to the spindle by reason of its interlocking relation with the spindle at 100

a point removed from the outer and free end of the tool. The inner end of the resilient supporting casing 32 is also provided with an enlargement or flange 42 perforated to receive the dowel pin 26. A suitable washer 43 of rubber or the like may be interposed between the shoulder 22 and the flange 40 of the metallic insert to assist in maintaining an air-tight joint. An internally threaded collar 44 is slipped on over the tool to clamp the casing and insert to the spindle, and to this end it is provided with an in-turned flange 46 between which and the flange of the rubber casing 32 is inserted an anti-friction washer 48 of metal and having a rounded cross section to prevent cutting of the rubber.

Recesses 60 may be provided in the reduced or inturned portion 46 for a spanner wrench to allow the collar 44 to be turned up tightly against the washer 48 so as to force the flange 40 against the washer 43 on the shoulder 22 of the spindle to make an air-tight joint. The washer 48 so reduces the friction between the collar 44 and the flange 42 of the rubber casing 32 that a very considerable pressure may be exerted upon the flange of said rubber casing without setting up torsional stresses to twist this end of the supporting casing with respect to the spindle.

There is thus provided a construction in which the tubular insert or anti-twisting means 30 is secured to the spindle, by interlocking engagement therewith at a point removed from the free end of the tool, both against torsional strains due to application of work to the tool and the axial stresses due to inflation of the tool, by the same clamping means which is utilized to secure the upper end of the rubber supporting casing 32. This clamping means is also arranged, as will be noted, to make an air-tight joint between the upper end of the supporting casing 32 and the rotatable hollow spindle 16. Lateral openings 50 are provided in the insert beyond the outer end of the stub 28 to allow the air pressure to inflate the supporting casing 32 along a major portion of its length, so as thereby resiliently to support and retain the sleeve 34 of abrasive material.

In order that the tubular insert 30 may be intimately and permanently bonded to the casing 32 over a limited area to resist the torsional strains at the outer end of the rubber casing 32, the latter is provided with a series of spaced flanges 52, each of which is perforated, as at 54, so that the rubber of the casing 32 will flow through said perforations 54 in the vulcanization of the casing and be molded around the flanges 52 so as to be intimately united with the outer end of the tubular insert. The rubber not only adheres to the insert by reason of being vul-

canized to it but is also interlocked with the metal of which the insert is composed. Experience has shown that the torsional stresses at the outer end of the resilient supporting casing 32 are very considerable and that such stresses are effectively resisted by portions of the rubber interlinked with the metal of the insert. 70

In the use of the machine, the abrasive cover or sleeve 34 is applied to the tool while the casing 32 is deflated, in which condition said cover slips easily over the rubber casing and air pressure is then applied to inflate the casing so as frictionally to engage the abrasive sleeve 34 to hold it on the tool and so as to form a cushion of air between the rubber casing 32 and the metal insert 30. The machine is then set in motion and the work presented to the tool. If the tool is to be used for buffing the breasts of heels, the operator will apply the heel in a horizontal position to the tool and move it to and fro to bring all parts of the breast of the heel into contact with the tool. The curvature of the tool is sufficiently less than that of the breast of the heel to permit access to all parts thereof. If the heel is scalloped, the operator may then present the shoe in an inverted vertical position and apply the scalloped portion of the breast of the heel to the tool. 80 90 95

Having thus described my invention, what I claim as new and desire to secure by Letters Patent of the United States is:

1. In an abrading machine having a shouldered rotatable spindle, a buffering tool adapted to be mounted on said spindle, said tool comprising a resilient supporting casing adapted to receive an abrasive cover and provided with an outwardly directed flange at one end, a similarly flanged insert within said casing and secured to the casing near its other end, and common means for clamping said flanges against the shoulder of said spindle. 100 105 110

2. In an abrading machine having a shouldered rotatable spindle, a buffering tool adapted to be mounted upon said spindle, said tool comprising a resilient supporting casing adapted to receive an abrasive cover and provided with an outwardly directed flange at one end, a similarly flanged insert within said casing and secured to the casing near its other end, positive interlocking means arranged to interengage and prevent relative rotation of said flanges and said shoulder, and means for clamping said flanges against the shoulder of said spindle. 115 120 125

3. In an abrading machine having a rotatable shouldered spindle, a buffering tool adapted to be mounted upon said spindle, said tool comprising a rubber supporting casing adapted to receive an abrasive cover and provided with an outwardly directed flange at one end, a flanged insert within 130

said casing extending substantially to the free end thereof, and means for clamping the flanges of said members against the shoulder of said spindle, said insert being provided with an opening adjacent to the free end of the casing, which opening is filled with rubber of the supporting casing.

4. A buffing tool adapted to be mounted upon a rotatable spindle having a shoulder, said tool comprising a molded rubber supporting casing adapted to receive an abrasive cover and provided with an outwardly directed flange at one end, a flanged insert within said casing extending substantially to the other end thereof, and means for clamping the flanges of said members against the shoulder of said spindle, said insert being provided with another flange adjacent to the unclamped end of the casing and having openings extending substantially parallel to the axis of the tool and filled with rubber of the supporting casing.

5. In an abrading machine, a rotatably supported spindle having a free end, a resilient casing adapted to receive and support an abrasive cover, the free end of said casing extending beyond the free end of the spindle, a tubular insert within said resilient casing secured to the free end of said casing and fitting the free end of said spindle, and means for clamping said tubular insert and the other end of said resilient casing to said spindle.

In testimony whereof I have signed my name to this specification.

GEORGE D. ALDERMAN.
